LISIMACO MACRIS, OF NEW YORK, N. Y.

SALT SHAKER.

Application filed December 5, 1925. Serial No. 73,332.

The purpose of the invention is to provide a salt-shaker which can be readily cleared when it becomes clogged, and to attain this result by a construction which can be cheaply manufactured, which permits of neat appearance in a table article, and which delivers the salt (or pepper) in a most satisfactory manner. According to the invention the top has a top wall which is formed with a plurality of narrow parallel slots or slits, and a movable cross-bar or member is provided having portions in the several slits for clearing the same by moving the member translationally lengthwise of the slits and transversely to itself.

In the accompanying drawings forming part hereof;

Fig. 1 is a central vertical sectional view through the top applied to the upper portion of a salt-shaker, the plane of the section being at right angles to the length of the slots;

Fig. 2 is an elevation looking at right angles to Fig. 1;

Fig. 3 is a plan view;

Fig. 4 is a perspective view of the top; and

Fig. 5 is a bottom perspective view of a comb-like clearing bar.

The salt-shaker top 2 illustrated in these views has a skirt or cylindrical wall 3 formed with screw-threads for engagement with the upper end of a salt-shaker body 4, and a flat top wall 5. Naturally, the top may be attached to the salt container in any suitable manner, or may be a permanent part thereof.

A plurality of long, narrow, parallel slots or slits 6 are cut in the top, or horizontal, wall 5, for the escape of the salt or pepper as the case may be. The slots are preferably five in number, but this may be varied.

A low, narrow bar 7 lies across the top, transversely of the slots, and has a row of thin prongs 8, 8^a bent downward into the slots, and projecting if desired some distance below them. Part or all of these prongs are bent somewhat under the wall to retain the device while permitting it to be moved lengthwise of the slot by pushing it with the thumb or finger. As shown, the prongs 8 which are bent from the end of the bar are bent under, while the prongs 8^a which are cut and bent from the body of the bar may be straight. The engagement of the bar in

this manner with the slotted wall is preferably comparatively tight so that the bar will remain frictionally fixed in the ordinary use of the shaker, but can be readily enough moved to clear the slots when they become clogged.

The bar 7, in addition to the downturned prongs, has upturned side edges 9. These afford a purchase for the fingers in moving the bar. The slits are preferably formed in the area of a square inscribed in the circle of the top, this square arm being slightly raised.

In the construction which has been described the thin sheet metal prongs are moved edgewise along the slits 6, these slits being correspondingly narrow. The bar 7 leaves the greater part, or a large part, of the length of the slits exposed. In this device, therefore, the salt is delivered through quite narrow slits, which give an adequate discharge without the danger of excessive flow that there is with comparatively short and wide openings, or large holes, the slits controlling the flow, and being kept clear by the clearing prongs, which are correspondingly narrow in the direction transverse to the direction of the clearing movement.

While the preferred embodiment of the invention has been described in detail, I do not wish to limit myself to the precise form and details. When the invention is used for pepper, it will be understood that the slits will naturally be finer than when for salt.

What I claim as new is:

1. A salt-shaker top having a top wall provided with a plurality of straight narrow parallel slits, and a bar lying crosswise of the slits and leaving the greater part of the length of said slits exposed, said bar being mounted for translational movement transverse to itself and lengthwise of the slits and having down-bent prongs in the slits arranged to move edgewise to themselves along said slits.

2. A salt-shaker top having a top wall provided with a plurality of parallel slots, and a bar lying on said wall crosswise of the slots and having an upturned edge and downturned prongs in the slots, certain of said prongs being bent under the wall to retain the bar while permitting it to be moved lengthwise of the slots.
